The ornamental design for an electro-optical distance-measuring instrument, as shown.

DESCRIPTION

FIG. 1 is a perspective view of an electro-optical distance-measuring device taken from the front, left and upper sides thereof, showing my new design.

FIG. 2 is a front elevational view of the electro-optical distance-measuring device of FIG. 1.

FIG. 3 is a rear elevational view of the electro-optical distance-measuring device of FIG. 1.

FIG. 4 is a left side elevational view of the electro-optical distance-measuring device of FIG. 1.

FIG. 5 is a right side elevational view of the electro-optical distance-measuring device of FIG. 1.

FIG. 6 is a top plan view of the electro-optical distance-measuring device of FIG. 1; and,

FIG. 7 is a bottom plan view of the electro-optical distance-measuring device of FIG. 1.
